SUGAR BOWL OR SIMILAR ARTICLE

Frank J. Benes, Lancaster, Ohio, assignor to Anchor Hocking Glass Corporation, Lancaster, Ohio, a corporation of Delaware

Original design application Apr. 20, 1967, Ser. No. 6,764. Divided and this application Nov. 16, 1967, Ser. No. 9,902

Term of patent 14 years

(Cl. D44—15)

FIG. 1 is an elevational view of a sugar bowl or similar article showing my new design;

FIG. 2 is a top view thereof; and

FIG. 3 is an end view thereof.

The present application is a division of copending United States design patent application Ser. No. 6,764, filed Apr. 20, 1967.

I claim:

The ornamental design for a sugar bowl or similar article, substantially as shown and described.
